MEANS FOR SECURING COVERS TO
RECEPTACLES

John W. Luke, St. Augustine, Fla.

Application August 1, 1936, Serial No. 93,748

3 Claims. (Cl. 24—256)

This invention relates to means for retaining closures on receptacles and is more particularly directed to fastening elements for securing a cover to a receptacle.

5 The invention contemplates a detachable clip for securing a pliable skirted cover, such as paper over the open end of a receptacle and retaining the cover in tight engagement with the walls of said receptacle.

10 An object of the invention is to provide a flexible metallic clip having a non-metallic covering thereon and adapted to grip the walls of any container in order to hold a cover for the same in proper position.

15 Another object of the invention is to provide a flexible rubber covered clip having portions for engaging the overhanging portions of a closure in order to retain the same in contact with the receptacle.

20 A further object of the invention is to provide a clip so constructed as to enable the clip to be manufactured in large quantities at a minimum expense.

25 A still further object resides in the provision of a retaining means in the form of a plurality of clips resiliently connected together as a unit.

30 A still further object of the invention is the provision of a temporary and inexpensive closure for a receptacle including a cover of sheet pliable material such as paper capable of conforming to the configuration of a receptacle and held in position by resilient members.

35 Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

40 Figure 1 is a perspective view of a receptacle showing the invention as used in connection therewith;

45 Figure 2 is a vertical sectional view taken substantially on the line 2—2 of Figure 1;

50 Figure 3 is a perspective view of one of the retaining elements forming a part of the invention and showing the resilient connecting band to which the clips may be secured;

55 Figure 4 is a sectional detail view taken substantially on a line 4—4 of Figure 3;

Figure 5 is a sectional detail view of another form of clip or retaining means.

Although the invention has been shown as utilized in securing a cover to a receptacle, it is to be understood that the invention may be used wherever it is found to have utility.

Referring to the drawing in detail and particularly to Figure 1, the invention has been illustrated as applied to a receptacle or bowl 6, the open end 8 of the same being covered or enclosed by means of a cover or closure 10 formed of pliable sheet material such as paper or the like and of a suitable size to provide depending portions adapted to contact with the wall of the receptacle. The cover 10 may be folded or crimped as at 11 around the periphery 12 of the open end 8 of the receptacle in order to provide 15 means for retaining it in place. A plurality of clips 13 serve to hold in tight engagement with the walls of the receptacle the crimped portion 11 of the cover 10 gripping the walls 14 thereby securing the cover over the open end 8 of the 20 receptacle as particularly shown in Figure 2. As the clips 13 are preferably of the same construction, it is only necessary to describe one in detail. The clip 13 as particularly shown in Figure 4 includes a flexible metallic strip 15 covered or 25 coated by a suitable yieldable material such as rubber fabric or other non-metallic material 16. The cover material 16 may be applied in any convenient manner, and if rubber is used, it may be vulcanized thereon or secured thereby by suitable cement. The use of latex, lacquer, enamel or other suitable material which will render the metal member non-oxidizable is also contemplated as covering for the strip 15 as the same has been found very satisfactory for such purposes. 30

35 Clips 13 are preferably of a substantially U-shaped configuration formed by bending the strip 15 upon itself providing leg portions 17 and 19. Leg portion 19 extends beyond leg portion 17 and has an enlarged portion 20 particularly 40 shown in Figure 3 preferably formed of the same material as that of the lining or cover 16 projecting outwardly on each side of leg 19. Leg portion 17 is bent inwardly toward leg portion 19 for the purpose of increasing the gripping action of the 45 clip. Clips 13 are preferably made of flexible material and are capable of being bent or compressed so that upon their application to the receptacle, the cover 10 is held in tight engagement by the clips against the walls of the receptacle 50 and due to the flexibility of the construction the clips are capable of being used with receptacles having walls of various degrees of thickness.

55 As illustrated in Figures 1 to 4, inclusive, a resilient band 21 of elastic or stretchable material

5 may be secured to one face 22 of the enlarged portion 20 of each clip, and as particularly shown in Figures 1 and 2 the clips when attached to the band 21 in this manner may be applied to the receptacle 6 as a unit, in which case the elastic 10 will stretch around the circumference of the receptacle or bowl. By such arrangement the depending portions of the skirt 25 of cover 16 are held in engagement with the outer surface of the bowl by band 21 thus providing a seal against the ingress of air and moisture to the interior of the bowl itself.

15 The device is particularly adaptable for use with receptacles such as bowls, pans and jars for containing food. I have found it desirable to provide a cover for such containers in order to maintain the food in proper condition and to prevent the odor of one food from permeating another, which frequently occurs when the food is placed 20 in refrigerators or the like, and in this connection I have found wax paper, Cellophane and other translucent cellulose derivatives serve the purpose very effectively permitting visibility of the contents of the container without necessity of removing the closure. The device herein described 25 has many advantages in that it will fit any container due to the elasticity of the band 21 and as any paper may be utilized, the necessity of having specially shaped closures particularly adapted for 30 each container is entirely eliminated.

Another construction of the clip is illustrated in Figure 5 in which the metallic strip 15 extends the full length of the rubber or fabric coating 16. In this form of the invention, the yieldable cover 35 for the metallic strip 15 may be preformed and provided with an opening to facilitate that strip 15 be inserted therein and later the opening being permanently sealed.

40 Although the clips 13 have been shown connected by the elastic band 21 for retaining the skirt portion 25, it is to be understood that the clips may be used independently of the band for securing the cover 16 in proper position. Due to the construction of the clips and particularly the 45 metallic strip 15 of the same, the clips may be used repeatedly without noticeable wear or loss of gripping strength or effect.

45 The cover retaining means or clips 13 in the form of the invention shown have been illustrated 50 as having a metallic member 15 provided with an outer cover of resilient material. However, I have found it very effective to omit the use of rubber covering and have the metallic member 15 coated with a lacquer or enamel, or other material 55 which will render the clips non-oxidizable. This type of construction will materially reduce the cost without interfering materially with the retaining action of the clips 13.

60 I have found the following process for rubber coating the metal strip in forming the completed clip very effective and comparatively inexpensive as the same eliminates the use of heavy and ex-

5 pensive machinery. This process resides in the use of a hot plate having a plurality of moulds or sectional dies having recesses of the proper desired configuration for the finished clip. A second plate adapted to be locked to the first plate, 10 is employed carrying the cooperating section of the dies which are provided with suitably spaced projections, acting as a matrix and adapted to conform to the recess carried by the heated plate. A strip of rubber formed to fit into each recess is 15 positioned thereon and a strip of metal placed on top of each rubber strip. The second plate having the projections is then placed over the first plate and pressure applied thereon which, to cause an intimate contact of the metal strip and rubber strip. The second plate is then removed and another strip of rubber placed over the metal strip in each recess. The second plate is again placed over the hot plate and locked in place, this pressure and heat is applied to obtain the proper vul- 20 canization of the rubber strips thus forming a closed envelope for the metal strips.

25 It is apparent that, within the scope of the invention, modifications and different arrangements may be made other than is herein disclosed, and the present disclosure is illustrative merely, the invention comprehending all variations thereof.

What I claim is:

30 1. A detachable retaining means for securing a pliable cover over the open end of a receptacle including a stretchable band for engaging the outer surface of said receptacle and holding the cover thereto; a plurality of clips attached to said stretchable band, said clips comprising a metallic bendable element having a yieldable covering 35 formed to a U-shaped configuration with one leg portion extending beyond the other for frictionally holding the pliable cover by gripping the walls of the receptacle.

40 2. A detachable means for securing a pliable cover over the open end of a receptacle including a plurality of clips for gripping the side walls of said receptacle; said clips comprising a metallic deformable element having a rubber coating formed to a substantially U-shaped configuration 45 having an enlarged leg portion which extends beyond the other and the clips being adapted to be shaped to conform with the lip of the receptacle for retaining the cover in position.

45 3. A detachable retaining means for securing a pliable skirted cover over the open end of a receptacle including a band formed of elastic material for securing the skirt portion of the cover in engagement with the outer wall of the receptacle; a plurality of bendable clips of substantially U-shaped configuration with a leg portion which extends beyond the other by which the clips are secured to said band, said clips made of deformable material for gripping the cover around portions of the inner and outer walls of the lip of 60 the container.

JOHN W. LUKE.
